UNITED STATES PATENT OFFICE.

EDMUND SPENSER TIDDEMAN, OF HORNCURCH, AND FREDERICK VERNON RUSSELL, OF LEYTONSTONE, ENGLAND, ASSIGNEES TO W. R. SYKES INTERLOCKING SIGNAL COMPANY LIMITED, OF CLAPHAM, LONDON, ENGLAND.

RAILWAY SIGNALING APPARATUS.

Application filed July 24, 1920. Serial No. 398,752.

(GRANTED UNDER THE PROVISIONS OF THE ACT OF MARCH 3, 1921, 41 STAT. L., 1313.)

To all whom it may concern:

Be it known that we, EDMUND SPENSER TIDDEMAN, of Wood End, Great Nelmes, Hornchurch, in the county of Essex, England, a subject of the King of Great Britain, and FREDERICK VERNON RUSSELL, of 17 Teesdale Road, Leytonstone, in the county of Essex, England, have invented certain new and useful Improvements in or Relating to Railway Signaling Apparatus (for which we have filed an application in England March 19th, 1917, Patent Number 138,208), of which the following is a specification.

This invention relates to railway signaling apparatus of that type designed on the one hand to apply the brakes of a train or railway vehicle and give a corresponding danger signal on passing a track-ramp, in both cases by mechanical means, and on the other hand to restrain the application of the brakes and indication of the danger signal, if the road is clear, by electrical means adapted to substitute a safety signal indication for that of the danger signal, the said electrical means embodying, it may be, a polarized relay, serving, on single line systems, for the purpose of discriminating between electrically-energized ramps which pertain on the one hand to signals for controlling traffic in the direction in which the train is running, and on the other hand to signals for controlling traffic in the opposite direction.

In such apparatus a lever or equivalent movable device, is caused to move into an operative position and enable a danger signal to be given, or not to be given, according to whether an electromagnetic device forming part of such apparatus is dead, or is energized by a signalman completing its circuit, as for instance through an insulated ramp on the line and an insulated shoe carried by a plunger or other movable device that forms part of the apparatus and is operated by the ramp when passing over the same and controls the action of the lever or equivalent device, hereinafter referred to for brevity and distinction as the controlled lever.

Signaling apparatus of the type referred

to is described in the specifications of former British Letters Patent Nos. 6499 of 1915 and 112,191 granted to one of the present applicants.

55

The present invention has for its object an improved form of such apparatus which will differentiate between the track-ramps appertaining to distant and home signals respectively in such manner that if, on the one hand, a distant signal in the "on" or danger position be passed the brakes may be released by the driver from the cab by the operation of a push valve, but if, on the other hand, a home signal in the "on" or danger position be over-run the brakes can only be released by the driver after he has descended from the cab to the permanent way and reset the apparatus.

60

A further object of the present invention is to provide means for bringing about the automatic application of the brakes if the shoe is broken away by encountering an obstacle on the permanent way.

65

According to this invention the apparatus is provided with a single spring-pressed detent adapted, when the plunger or other movable device which carries the shoe (hereinafter referred to as the plunger) has been raised to a predetermined height by the passage of its shoe over a track-ramp appertaining to a home signal in the "on" or danger position, to engage said plunger and to prevent the return thereof to its normal position until the apparatus is reset, and with means for rendering said detent inoperative when the plunger is raised to said height by the passage of its shoe over a track-ramp appertaining to a home signal in the "off" or clear position, said detent being also inoperative when the plunger is raised to a height less than the predetermined height by the passage of its shoe over a track-ramp appertaining to a distant signal whether in the "on" or "off" position, for which purpose the track ramps appertaining to distant signals are designed to give less lift to the plunger than those appertaining to home signals, and said detent being connected with a concurrently movable notched plunger, whereof the notch is adapted to be engaged by a finger movable

80

85

95

100

as one with the controlled lever in order that the detent may be rendered inoperative when the controlled lever is in the inoperative position.

5 The present invention is applicable to steam, compressed air, or vacuum brakes, as is the case with the said prior inventions, and a further object of the present invention, when applied to a compressed air or 10 a vacuum brake, is to bring about a partial application of the brake and an audible indication when a distant signal in the "on" position is passed, and a full application of the brake and, it may be, a different audible 15 indication when a home signal in the "on" position is over-run.

The invention is illustrated by the accompanying drawings wherein Figure 1 is a partly sectional elevation of one form of apparatus constructed in accordance with this 20 invention, the constructional details and the arrangement of similar parts being substantially as described and illustrated in the specifications of the prior patents 25 aforesaid. Figure 2 is a section on the line 2—2, Figure 1, parts being omitted for the sake of clearness; Figure 3 is a sectional plan on the line 3—3, Figure 1; Figure 4 is a cross section on the line 4—4, Figure 1; 30 Figure 5 is a face view of a portion of Figure 1, parts being omitted for the sake of clearness; Figure 6 is a section on the line 6—6, Figure 5; Figure 7 is a similar view to Figure 5 shewing an additional feature of 35 the invention and Figure 8 is a cross-section on the line 8—8, Figure 7.

In order that the application of the present invention may be more readily understood reference will first be made to details 40 of the previous constructions, as arranged for bringing about the operation of air-pressure brakes.

11 is a plunger fitted to slide vertically in guides 12, 12, carried by a plate 13 mounted 45 upon the framing of the locomotive, the plunger tending to descend in its guides under the stress of a spring 14. The plunger 11 is in two mutually overlapping sections, having their contiguous faces serrated and 50 united by bolts 15 so as to enable the effective length of the plunger to be adjusted by moving the one section relatively to the other; the lower section serving to carry an insulated contact-shoe 16 adapted to slide over insulated ramps (not shewn) which 55 are mounted in the permanent way and whereby the plunger 11 as a whole is forced upwards in its guides 12, 12, against the tension of the spring 14.

60 17 is the controlled lever (already referred to) which is fulcrumed at 18 to the plate 13 and normally held in the position shewn in Figure 1 by a projection 19 upon the lever abutting against the extremity of one arm 65 of a bell-crank trigger-lever 20 which is

fulcrumed to the plunger 11 at 21 and which normally rests upon a stop 22 on the plunger, a spring 23 tending to retain the lever 20 in this position. So long as the controlled lever 17, by its projection 19, abuts 70 against the trigger lever 20, it holds in their relatively straightened positions the limbs 24, 25 of a toggle whereof the limb 24 is pivoted to the lever 17 at 26, whilst the limb 25 is pivoted to the plate 13 at 27, the middle joint 28 of the toggle being raised when the toggle as a whole is straightened. 29 is a counterweight carried by an extension of the limb 25 and tending to straighten the toggle. 30 is the armature of an electro-magnet 31, one end of the winding of which is earthed whilst the other is connected with the wire leading from the shoe 16 to the electric bell or other electrically operated alarm within the cab of the locomotive. The 80 electromagnet 31 is mounted on the plate 13, whilst the armature 30 is pivotally carried by the toggle limb 25 so that, when the electro-magnet 31 is energized as a result of the shoe 16 passing over an electrically 90 "live" ramp, the consequent attraction of its armature 30 (assisted by the weight 29) will cause the toggle 24, 25 to be held in the straightened position and the controlled lever 17 to be held in the normal position indicated in Figure 1. When, as a result of the shoe 16 passing over an electrically 95 "dead" ramp, the toggle-centre 28 is allowed to drop and the lever 17 assumes the abnormal position, the subsequent straightening 100 of the toggle, and consequent restoration of the controlled lever 17 to normal position, can be effected by means of a bell-crank resetting lever 32, which is fulcrumed to the plate 13 at 33 and controlled by the piston 105 rod 34 of a resetting-cylinder 35 which communicates, by way of a pipe 36, with the main air-pressure reservoir of the locomotive, the connection being controlled by a manually-operated resetting-valve (not 110 shewn). The piston-rod 34 is attached to one arm of the lever 32, whereof the other arm has pivoted to it a link 37 having a pin-and-slot connection at 38 with the limb 24 of the toggle.

Upon the plate 13 is mounted the casing 39 of an air-valve for controlling the application of the air-pressure brakes on the train and the giving of an alarm signal in the cab of the locomotive. So long as the controlled lever 17 is in normal position, it bears against the spindle 40 of said valve which is held closed by said lever. The valve in the casing 39 controls communication between the interior of said casing and a pipe 41 connected with the train air-pipe (not shewn), whilst the casing 39 is provided with a branch passage from which a pipe 42 leads through a distributing valve (to be described hereinafter) to whistles or equiva- 125 130

lent alarms (not shewn) within the cab. Normally the lever 17 holds the valve in the casing 39 closed against its seat, but when said lever is released the air pressure within 5 the pipe 41 causes said valve to open, and the air which escapes from said pipe passes by way of the pipe 42 to the distributing valve, and at the same time brings about the application of the air pressure brakes on 10 the train in a well-known manner.

In accordance with the present invention the following additions are made. To the rear face of the plate 13 is secured a housing 43 provided with a guide 44 carried 15 axially within a cup 45 screwed into the housing 43. A bolt or detent 46, provided at or about the centre of its length with a peripheral flange 47, is slidable in the guide 44 and in an aperture 48 in the plate 13 20 against the pressure of a coaxially arranged coiled spring 49 which abuts at its one end against the flange 47 and at its other end against the end of the cup 45, and which tends to force the end of the bolt through 25 the aperture 48 and through a corresponding aperture 50 in the plunger 11 when said plunger is raised to a predetermined height by the passage of its shoe 16 over a track-ramp appertaining to a home signal. The 30 housing 43 also serves as a guide for a plunger 51 for resetting the apparatus after the brakes have been applied consequent upon a home signal in the "on" position having been overrun. This resetting plunger 35 51 extends at its one end through the rear wall of the housing 43 and is provided with a handle 52 and at its other end through the plate 13 and is formed with a notch 53 for a purpose which will be hereinafter described. Pivotaly mounted at 40 54 upon the rear face of the plate 13 is a rocking bar 55 the opposite ends of which are pivotally connected at 56 and 57 with the spring-pressed bolt 46 and the resetting 45 plunger 51 respectively, so that these two members will move simultaneously and oppositely. Integral with the boss 58 of the controlled lever 17 is a finger 59 adapted to engage the notch 53 in the forward end 50 of the resetting plunger 51 in such manner that as long as the finger 59 is in engagement with the notch 53 the resetting plunger 51 and consequently the spring-pressed bolt 46 are prevented from moving oppositely; and, 55 as a result, when the controlled lever 17 is maintained in its normally inoperative position through the agency of the electromagnet 31 which is energized by the passage of the shoe 16 over a track-ramp which 60 is electrically live, and which appertains to a home signal in the "off" position, the spring-pressed bolt 46 is prevented from engaging the aperture 50 in the plunger 11. If, however, the track ramp appertaining 65 to a home signal in the "on" position is

over-run the controlled lever 17 is caused to move into an abnormal or operative position, the finger 59 is moved out of the notch 53, and the resetting plunger 51 and the spring-pressed bolt 46 are free to move 70 simultaneously and oppositely under the action of the spring 49 when the plunger 11 is raised to the predetermined height, the forward end of the spring pressed bolt 46 engaging the aperture 50 in the plunger 11 75 and preventing the brakes being released by the driver and the parts restored to their normal positions as set forth in the said prior specifications, until the driver has descended from the cab to the permanent way 80 and disengaged the spring-pressed bolt 46 from the plunger 11 by pressing in the resetting plunger 51.

When the invention is applied to a compressed air or to a vacuum brake the partial 85 application of the brake and the giving of an audible indication when a distant signal in the "on" position is passed and the full application of the brake and a different audible indication when a home-signal in 90 the "on" position is over-run, are accomplished by interposing in the pipe 42, which leads from the air-valve casing 39 for controlling the application of the brake to the whistle, a two way valve adapted to connect 95 with said air-valve casing 39 the one or the other of two pipes 60, 61 of relatively different diameters and fitted with different sounding whistles (not shewn). The two-way valve is constituted by a pair of pistons 100 62, 63 mounted upon a piston rod 64 and slideable within a cylinder 65 secured to the plate 13, said cylinder 65 having three ports 66, 67 and 68 connected with the air valve casing 39 and each of the two pipes 105 60 and 61, said ports being so spaced relatively to the distance between the pistons 62 and 63 that the casing 39 may be placed in communication with the one or the other of said pipes 60 and 61, whilst the piston 110 rod 64 passes out of the lower end of the cylinder 65 and is slotted as at 69 to receive a turned pin 70 upon a bracket 71 secured to the plunger 11. Normally the air-valve casing 39 is in communication with 115 the smaller, 61, of the two pipes, and its whistle, and the slot 69 in the lower end of the piston rod 64 is of such length that when the plunger 11 (and consequently the turned pin 70 in said slot 69) is raised 120 by the passage of its shoe 16 over a track-ramp appertaining to a distant signal in the "on" position the two-way valve is unaffected and the rush of air permitted by the opening of the air valve in the casing 39 as the 125 brake is applied passes through the smaller pipe 61 and its whistle, the pipe 61 being of such size that the rush of air is restrained and the application of the brake is partial only. If, however, the plunger 11 is raised 130

by the passage of its shoe 16 over a track ramp appertaining to a home signal in the "on" position, the additional lift of the plunger 11 causes the turned pin 70 to engage and raise the piston rod 64, thus establishing communication between the air-valve casing 39 and the larger pipe 60 and its different sounding whistle, said pipe 60 being of such size that the rush of air is not restrained and the brake will be fully applied.

If desired that full brake pressure should be applied both when a distant signal in the "on" position is passed and when a home signal in the "on" position is overrun the two pipes 60, 61 the one or the other of which is adapted to be placed in communication with the pipe 42, are made of the same diameter, and serve to connect the air-valve casing 39 with the one or the other of the two whistles; or a single pipe may lead to a single whistle, or if it is desired to use a single whistle and effect the partial and full application of the brakes at the distant and home signals as hereinbefore set forth, the smaller pipe 61 may be connected with the larger pipe 62 by a T-piece.

In order that the brakes may be automatically applied if the shoe 16 is broken away by encountering an obstacle on the permanent way, the stop 22 whereon the bell-crank trigger lever 20 normally rests is constituted as shewn in Figures 7 and 8 by a second bell-crank lever 72 (hereinafter referred to as the bell-crank stop lever) which is pivoted at 73 to the plunger 11 so as to lie in a vertical plane transversely of the apparatus and is held by a two-part rod 74, 75 which is adjustable in length, the part 74 being formed with a socket 76 into which the threaded end of the part 75 engages, and said rod is pivotally connected at its upper end at 77 with the bell-crank stop lever 72, whilst its lower end is secured at 78 to and electrically insulated from the shoe 16. Normally the rod 74, 75 holds the bell crank stop lever 72 in the position shown in full lines in Figure 8 to constitute a stop, but if the shoe 16 is broken away the bell-crank stop lever 72 is pulled down by the rod 74, 75 to the position shewn in dotted lines in Figure 8, allowing the bell crank trigger lever 20 to drop to the position shewn in dotted lines in Fig. 7, so that the controlled lever 17 may be caused to move into an operative position and bring about the application of the brakes.

The track ramps may be placed in the four foot way, alongside the track, or in other convenient position, the apparatus being so disposed on the engine as to coat therewith as hereinbefore set forth.

Having now particularly described and ascertained the nature of our said inven-

tion, and in what manner the same is to be performed, we declare that what we claim is:—

1. In railway signaling apparatus, the combination of means for controlling the application of the brakes, mechanism, including a vertically slideable plunger and a controlled lever, controlling the operation of said means, a contact shoe carried by said plunger and adapted to pass over track ramps of different heights operatively connected with a home signal and a distant signal respectively, a single spring-pressed detent adapted, when the plunger has been raised to a predetermined height by the passage of its shoe over a track ramp relating to a home signal and the latter is in the "danger" position, to engage said plunger and prevent the return thereof to its normal position, means for rendering said detent inoperative when said shoe passes over said track ramp with said home signal in the "off" position, said detent being inoperative also when the plunger is raised to a lesser degree by the passage of the shoe over a track ramp relating to a distant signal, regardless of the position of said signal, a notched plunger operatively connected with said detent and movable concurrently therewith, and a finger movable with said controlled lever and adapted to engage said notch whereby said detent is rendered inoperative when the controlled lever is in its inoperative position.

2. In railway signaling apparatus, the combination of means for controlling the application of the brakes, mechanism, including a vertically slideable plunger and a controlled lever, controlling the operation of said means, a contact shoe carried by said plunger and adapted to pass over track ramps of different heights operatively connected with a home signal and a distant signal respectively, a single spring-pressed detent adapted, when the plunger has been raised to a predetermined height by the passage of its shoe over a track ramp relating to a home signal and the latter is in the "danger" position, to engage said plunger and prevent the return thereof to its normal position, and means for rendering said detent inoperative when said shoe passes over said track ramp with said home signal in the "off" position.

3. In railway signaling apparatus, the combination of means for controlling the application of the brakes, mechanism, including a vertically slideable plunger and a controlled lever, controlling the operation of said means, a contact shoe carried by said plunger and adapted to pass over track ramps of different heights operatively connected with a home signal and a distant signal respectively, and a single spring-pressed detent adapted, when the plunger has been

raised to a predetermined height by the passage of its shoe over a track ramp relating to a home signal and the latter is in the "danger" position, to prevent the return of said 5 plunger to its normal position.

4. In railway signaling apparatus, the combination of means for controlling the application of the brakes, mechanism, including a vertically slideable plunger and a controlled 10 lever, controlling the operation of said means, a contact shoe carried by said plunger and adapted to pass over track ramps of different heights operatively connected with a home signal and a distant signal respectively, 15 a single spring-pressed detent adapted, when the plunger has been raised to a predetermined height by the passage of its shoe over a track ramp relating to a home signal and the latter is in the "danger" position, to 20 prevent the return of said plunger to its normal position, and manually operated means for restoring said detent to its inoperative position, said means being so located as to 25 compel the engine driver to descend from the engine cab to the permanent way to operate the same.

5. In railway signaling apparatus, the combination of means for controlling the application of the brakes, mechanism, including a vertically slideable plunger and a controlled 30 lever, controlling the operation of said means, a contact shoe carried by said plunger and adapted to pass over track ramps of different heights operatively connected with a home signal and a distant signal respectively, 35 a single spring-pressed detent adapted, when the plunger has been raised to a predetermined height by the passage of its shoe over a track ramp relating to a home signal 40 and the latter is in the "danger" position, to engage said plunger and prevent the return thereof to its normal position, means for rendering said detent inoperative when said shoe passes over said track ramp with said

home signal in the "off" position, said de- 45 tent being inoperative also, when the plunger is raised to a lesser degree by the passage of the shoe over a track ramp relating to a distant signal, regardless of the position of said signal, a finger connected with 50 said controlled lever and movable therewith, a notched plunger arranged to engage said finger and a rocking bar connecting said notched plunger and detent whereby the latter is rendered inoperative when said finger 55 is engaged by said notched plunger.

6. In railway signaling apparatus, the combination of means for controlling the application of pneumatically operated brakes, 60 said means including air conduits of different cross-sectional area, mechanism, including a vertically slideable plunger, controlling the operation of said means, a two-way valve controlling said air conduits, and a slotted piston rod connected with said plunger whereby said valve is operated only when the plunger is raised to a predetermined height to alternately open said conduits and thereby bring about a partial or 65 complete application of the brakes. 70

7. In a railway signaling apparatus, the combination of means for controlling the application of the brakes, mechanism, including a vertically slideable plunger and a controlled lever, controlling the operation of 75 said means, a contact shoe carried by said plunger and adapted to pass over track ramps, a bell-crank trigger carried by said plunger and arranged to control said lever, a bell-crank lever mounted on said plunger 80 and constituting a stop upon which the bell-crank trigger normally rests, and a rod connected with said shoe and with said bell-crank lever whereby the latter is maintained in its operative position. 85

EDMUND SPENSER TIDDEMAN.
